UNITED STATES PATENT OFFICE.

WILLIAM C. LANGSTON, OF OAK PARK, ILLINOIS, ASSIGNOR OF ONE-HALF TO WALTER I. COBLE, OF CHICAGO, ILLINOIS.

GAS-FIRED HOT-AIR FURNACE.

Application filed January 17, 1923. Serial No. 613,101.

To all whom it may concern:

Be it known that I, WILLIAM C. LANGSTON, citizen of the United States, residing at Oak Park, in the county of Cook and State 5 of Illinois, have invented a certain new and useful Improvement in Gas-Fired Hot-Air Furnaces, of which the following is a full, clear, concise, and exact description, reference being had to the accompanying drawings, forming a part of this specification.

The invention relates to hot air furnaces, such as are ordinarily employed to heat dwellings and other structures.

The invention has among its various objects the provision of a heater or furnace which comprises a cool air zone or region, a combustion chamber, air heating zones or regions, and, in addition thereto, provides a hot air zone or region from which the heated air may be withdrawn and transmitted to the various portions of the dwelling, or other structure, which it is desired to heat.

It is a prime object of the invention 25 to provide a combustion chamber which is composed of a hollow element which, when arranged in position in the heater or furnace, extends transversely across the interior of the furnace casing and in the path 30 of the air to be heated.

It is a further object of the invention to provide a combustion chamber which is composed of a plurality of these hollow or chambered elements and to arrange said 35 elements relatively to each other, so that a space will be provided between each of them, through which the air to be heated may flow and become heated during its passage from the cool air zone to the hot air 40 zone of the furnace.

In addition, it is an object to provide a combustion chamber, the construction of which produces a plurality of communicating, chambered elements which are connected with each other in a manner to provide a unitary construction, and in which said chambered elements are arranged or disposed relatively to each other to provide a passage for the air as it travels from the 45 cool air zone to the hot air zone of the furnace.

It is a further object to construct said combustion chamber so that the fumes and other products of combustion are prevented 55 from escaping from the combustion chamber

and becoming mixed with the heated air which is transmitted to the rooms of the dwelling or other structure to be heated.

It is a further object to associate with a combustion chamber of the character above referred to suitable burners, designed to burn gas, oil, or other suitable fuel, and to arrange said burners so that the fumes and odors which result from their use are prevented from escaping into the furnace casting or the room in which the furnace is located. Gas burners are shown in the drawings and referred to herein.

It is a further object of the invention to provide each of the hollow elements forming the combustion chamber with a suitable structure whereby access to the interior of the combustion chamber may be readily had, should this at any time become necessary or desirable, and, in addition, to provide means whereby air may be introduced into the combustion chamber and also regulated.

The invention will be explained and more readily understood when read in conjunction with the accompanying drawings, in which one embodiment of which the invention is susceptible is illustrated, it being obvious that changes and modifications may be employed without departing from the spirit of the appended claims forming a part hereof.

In the drawings,

Figure 1 is a central, vertical section of a furnace constructed according to one embodiment of the invention;

Figure 2 is a section taken on line 2—2 of Figure 1;

Figure 3 is a perspective view of the combustion chamber employed in the structure illustrated in Figures 1 and 2;

Figure 4 is a section taken on line 4—4 of Figure 3;

Figure 5 is a section showing in detail the connection between the ends of the hollow elements forming the combustion chamber, the side walls of the casing forming the furnace and the frame to which a closure for the combustion chamber is secured.

In the particular embodiment of the invention herein illustrated, the furnace casing is of a substantially rectangular outline and is constructed to produce a cool air zone or region 10. One wall of the furnace, such as 11, is provided with an opening 12, through which cold air is admitted into the

cool air zone. The wall of the furnace is provided with a shelf 13 and an opening 14 through which a container 15, in which a suitable amount of water is confined, may 5 be inserted into the zone 10. The container 15 is employed in the structure to afford the necessary humidity to the air which materially increases the heat carrying capacity of the air and adds to the efficiency of the 10 heater.

An air heating zone or region 16 is arranged above the zone or region 10 and is formed by the several corner wall portions 17, 18, 19, and 20 which are secured to the 15 combustion chamber generally designated 21 and also to the upper edges of the wall forming the zone 10.

The combustion chamber is formed by means of a top wall 22 and a bottom wall 20 23 which are each connected with the side walls 24, 25, 26, and 27 in any suitable manner, as by bolts, rivets, or may be, in addition, welded together to provide the seal necessary to prevent the escape of the fumes 25 and other products of combustion.

The side walls 24, 25, 26, and 27 of the combustion chamber and the associated wall formations of the corner portions 17, 18, 19, and 20 cooperate to define the zone 16 and 30 produce spaces which provide the passages 28, 29, 30, and 31, through which the air passes from the cool air zone 10 into contact with the walls of the combustion chamber 21 and thence to the hot air zone or 35 region 32 which is arranged above the zone 16 and the combustion chamber 21. The hot air zone or region is maintained through the cooperation of a cover 33 having a plurality of hot air outlets and pipes 34, 34, 40 through which the heated air is conducted to the various portions of the structure to be heated.

The walls forming the zone 32 are provided with an annular collar 35, which, 45 through the medium of the rivets 36 is secured to the walls 17, 18, 19, and 20 which form the zone or region. The collar provides a means for holding the wall 37 forming and defining part of the hot air zone in 50 its proper relative position with respect to the remaining structure.

The combustion chamber generally designated 21 is formed in a manner to provide a plurality of communicating hollow arms 38, 39, 40, and 41, the walls 24, 25, 26, and 27 forming the sides thereof, and the plates 22 and 23, respectively, providing the top and bottom thereof. The plates 22 and 23 are each formed to provide a right 60 angled cut-out portion 42, as clearly shown in Figures 2 and 3, the resultant structure producing arms or extensions 43. The side and end edges of these extensions, such as 43, are bent at an angle to the main portion of the plate; as indicated at 44 and 45,

and the bent sides 44 are riveted or otherwise secured to the walls 24, 25, 26, and 27 which are, respectively, arranged adjacent thereto. As before stated, the extremities of these extensions, such as 43, are bent, as 70 indicated at 45, to provide flanges whereby the structure may be secured to a frame 47, to which a door, such as 48, is hingedly secured, and also to the wall 11, surrounding the cool air zone 10. The opposite ends 75 of each of the walls 24, 25, 26, and 27 are each provided with a relatively long flange 46, which is designed to be riveted, welded, or otherwise secured to the edges of the walls 17, 18, 19, and 20, which form the outer portion of the casing adjacent the combustion chamber 21. The open ends of the chambers formed by the walls 24, 25, 26, and 27 and the plates 22 and 23 are 80 each provided with the frame 47, to which the door 48 is hingedly secured and, in addition, is provided with the apertures 49, through which air may enter the combustion chamber. The combustion chamber formed by the various elements 22, 23, 24, 25, 26, and 27 is provided with an opening 47a, through which the products of combustion may escape from the combustion chamber. Each of the chambers 38, 39, 40, and 41 has arranged therein a burner of suitable form and size, which extends into the chamber through an aperture 50 provided in the frame 47. In the present structure a burner, such as 51, extends from one chamber, such as 41, to the chamber 39 and the other chambers, such as 38 and 40 are each, respectively, provided, with burners 52 and 53. The outermost ends of these burners are connected to the supply pipe 54 which, in turn, is connected to a main supply pipe 55. Each of the burners 51, 52, and 53 is provided with a valve 56 which is of that type which controls the amount of fuel passing to the burner, and, in addition, controls the flow of air to the burner. It will be apparent that one or more of the burners may be employed at any time, depending on the amount of heat which is desired.

By referring particularly to Figures 4 and 5, it will be noted that the structure utilized in the formation of the combustion chamber and its connection with the remaining structure provides a connection between the outer casing of the furnace which positively prevents the products of combustion from finding their way from the combustion chamber into the interior of the casing provided by the walls forming the several regions or zones 10, 16, and 32, and, in addition, prevent the fumes and other products of combustion from finding their way into the room in which the furnace is located.

It is further manifest that the combustion chamber is arranged transversely of the casing forming the furnace and cooperates with

the casing to provide passages between it and the casing through which the air flows from the cool air zone to the hot air zone while being heated.

5 It will be evident that the construction and arrangement of the combustion chamber permits the use of a chamber of this character which is of a relatively large dimension and thus the time necessary for heating the air will be materially reduced and the heat units consumed also be lessend, all of which cooperates to increase the efficiency of the structure.

Having thus described the invention, what 15 I claim and desire to secure by Letters Patent is:

1. A combustion chamber providing a unit adapted to be arranged within and transversely of a main casing for a furnace 20 having an air inlet and outlet, said chamber having communicating radially arranged hollow arms or branches which extend to each of the walls of said casing and are provided with doors at their outer ends, said 25 unit being adapted to be arranged between the inlet and outlet of the main casing so that air entering the casing may pass through the space provided between the ra-

dially arranged hollow arms of the combustion chamber, and said radially arranged 30 hollow arms being adapted to have burners arranged therein which extend through the main casing and lengthwise of and within said arms.

2. In a heater the combination with a 35 casing having a hot air chamber and a cold air chamber, of a combustion chamber positioned between said air chambers, said combustion chamber comprising a plurality of upwardly extending angular shaped side 40 wall members, flanges on the lateral edges of said angular members riveted to said casing, and upper and lower end wall members having flanged edges riveted to said angular members and to the casing whereby said 45 combustion chamber is sealed from said hot and cold air chambers, and whereby said combustion chamber has a plurality of branched arms radiating outwardly to the said casing, and a burner within each of 50 said arms.

In witness whereof, I hereunto subscribe my name this 11 day of January, A. D. 1923.

WILLIAM C. LANGSTON.
